Olga M. Greiser, 502 1st Ave. NE., Aberdeen, S. Dak.

Filed Feb. 17, 1961, Ser. No. 63,980

Term of patent 14 years

(Cl. D29—1)

The FIGURE on the drawing is a perspective view of an artificial Christmas tree showing my new design.

The side opposite that shown is substantially similar in appearance as the side shown.

An essential part of my design is the use of relatively wide strips of ribbon arranged in closely bunched relation so that the tree has a substantially full appearance.

I claim:

The ornamental design for an artificial Christmas tree, as shown and described.
